UNITED STATES PATENT OFFICE.

EDWARD A. COADY, OF NEW YORK, AND FREDERIC W. OLMSTEAD, OF HEMPSTEAD, NEW YORK, ASSIGNORS, BY MESNE ASSIGNMENTS, TO FREDERICK CONLIN, OF WESTFIELD, NEW JERSEY.

ART OF ELECTROPLATING.

Application filed December 11, 1924. Serial No. 755,144.

To all whom it may concern:

Be it known that we, EDWARD A. COADY and FREDERIC W. OLMSTEAD, citizens of the United States, and residents, respectively, of New York, county of New York, and State of New York, and Hempstead, county of Nassau, and State of New York, have invented certain new and useful Improvements in the Art of Electroplating; and we do hereby declare the following to be a full, clear, and exact description of the invention, such as will enable others skilled in the art to which it appertains to make and use the same.

This invention relates to an improved brush for electrolytically applying metals, such as nickel, to conducting surfaces. It has previously been proposed to apply nickel coatings or platings to conducting surfaces by means of a brush with an anode arranged so that electrolysis takes places in the brush. The present invention relates more particularly to improvements in the construction of the brush employed in such operations; and this invention provides an improved brush which is easily handled, which enables an expeditious and efficient application of such metallic coatings, which enables the application of metallic coatings of good physical quality and of good appearance, and which has other important advantages which will appear from the following description and illustration.

In a brush for this purpose described in an application of Frederick Conlin filed January 12, 1925, Serial No. 1831 the anode is arranged within the bristle head of the brush so as to be wholly immersed in plating solution retained by the bristles of the brush. The anode is thus submerged in plating solution when the brush is in use so that the maximum area of the anode is exposed and so that a more uniform distribution of the flow of current through the electrolyte retained in the brush is promoted. Uniformity of distribution of the plating current assists in producing a metallic deposit of good physical properties and avoids burning of the metallic coating due to excessive current density over localized areas.

In the improved brush of the present invention, the anode is similarly arranged within the bristle head of the brush and so as

to be wholly immersed in plating solution retained by the bristles of the brush, and a substantially rigid apron is arranged about the brush bristles so as to prevent any contact of the anode in the brush with the surface being plated while nevertheless allowing free movement of the brush bristles. Where no protection is provided to prevent contact between the anode and the surface being plated, the flexing of the brush bristles may expose the anode which may thus be contacted with the surface being plated. Such contact results in short-circuit causing excessive current flow and tending to mar the surface by burning. The physical contact of the anode also may mar the surface being plated. By providing a substantially rigid apron about the brush bristles in the improved brush of the present invention, however, such contact is prevented without sacrificing free movement of the brush bristles or the ease of applying the brush in the plating operation.

This apron is advantageously flared outwardly away from the bristles of the brush toward the applied end of the bristles to allow them to move freely within the apron. The apron need not completely enclose the anode within the brush. The bristles, as arranged in a body in the brush, have a maximum angle of flexure beyond which no ordinary pressure applied in using the brush will bend them. In the improved brush of the present invention, advantage is taken of this maximum angle of flexure by arranging the apron so that the anode never crosses any straight line between the lower edge of the apron and the outer edge of the bristles in the position of maximum flexure. In this way, a materially shorter and lighter apron can be made to fully protect the anode from contact with the surface being plated.

The electrolysis of the plating solution in the brush may frequently be accompanied by the liberation of gas. The movement of the bristles of the brush over the anode immersed therein largely prevents polarization, but, where the gas liberated is confined in the brush, a somewhat similar result may be caused mechanically by displacement of the electrolyte about the anode by the gas liberated and confined in the brush. This causes overheating, reduces the capacity of

- the brush and has other objectionable effects. In the improved brush of the present invention, means may be provided for relieving any such gases as they are formed.
- 5 The provision of gas relieving means is particularly advantageous where an otherwise gas tight apron is employed, but certain advantages are obtained by the provision of gas relieving means in brushes without
- 10 aprons.

15 The invention will be further described in connection with the accompanying drawings which show several brushes embodying the invention, but it will be understood that this further description and illustration are for the purpose of exemplification and that the invention is not limited thereto.

In the accompanying drawings:

20 Fig. 1 represents, in section, a flat brush embodying the invention, on line 1—1 of Fig. 2,

Fig. 2 is a side view of the brush illustrated in Fig. 1,

25 Fig. 3 is a fragmentary view showing a somewhat modified type of brush head,

Fig. 4 represents, partly in section, a modified type of brush embodying the invention,

30 Fig. 5 represents, partly in section, a circular brush embodying the invention, and

Fig. 6 is a section on line 6—6 of Fig. 5.

The brush illustrated in Figs. 1 and 2 is made up of a separable brush head 7 and a handle 8. The brush bristles 9 are suitably secured in the brush head 7. The handle 8 may be of hard rubber or other suitable insulating and impervious material and the brush head 7 may also be of insulating material such as hard rubber. The bristles 40 may be set in rubber in the head as indicated at 10 in the drawing. The head 7 is provided with an apron 11 extending downwardly about the bristles 9 and flaring outwardly therefrom. The flare of the apron 45 advantageously corresponds to the natural curve of the brush bristles when in use, and the lower edge of the apron is rounded off to avoid undue wear of the bristles. This apron may be integral with the brush head, 50 and advantageously the entire brush head comprising the bristle settling and the apron are integral, as illustrated in Figs. 1 and 2.

55 A hole 12 is provided through the brush head in alignment with a corresponding hole 13 extending through the handle. An anode 14 is supported within the bristles 9 by means of a shank 15 extending upwardly through the holes in the brush head and handle. The edges of the anode are suitably beveled or rounded to avoid undue wear of the bristles. The upper end of the shank 15 is threaded and is arranged to engage an adjusting nut 16 and a lock nut 17, 60 the adjusting nut 16 cooperating with a col-

lar 18 fastened to the upper end of the handle 8. By means of the adjusting nut 16, the anode 14, is thus made adjustable toward and away from the applied end of the brush bristles. A clamp nut 19 is provided for making the electrical connection to the anode.

70 The apron 11 serves to prevent any contact between the anode 14 and the surface to which the exposed end of the bristles are applied in the plating operation while at the same time allowing full and free movement of the bristles. As in the brush illustrated in Fig. 1, this result may be accomplished without extending the apron downwardly 80 far enough to completely enclose the anode but a lighter and shorter apron may be employed. As will be apparent by reference to Fig. 1, before the anode 14 can contact with a surface being plated it must protrude 85 through the brush bristles. The brush bristles, however, offer a certain resistance to flexure which gradually increases as they are bent and which, with a body of bristles as in the brush illustrated, becomes so great 90 at an angle of maximum flexure that no ordinary pressure will further displace the bristles. With ordinary brush construction, this angle of maximum flexure amounts to about 27° to 30° from the surface to which 95 the brush is applied. Accordingly, in the improved brush of the present invention, the edge 20 of the apron 11 is arranged so that no straight line from it to the adjacent point on the lower edge of the anode, as at 100 21, makes an angle of less than about 27° with a surface normal to the axis of the brush. In other words, the angle between the line A—B and the axis of the brush is advantageously equal to or greater than 105 about 63° but need not be 90°.

105 The apron 11, in the brush illustrated in Figs. 1 and 2, is provided with a series of apertures 22 adjacent the handle end or fixed end of the brush bristles and just below the bristle setting 10. A vent 23 is also provided in the upper end of the handle communicating with the holes 12 and 13 through the brush head and the handle. Any gas liberated by the electrolysis taking 110 place within the brush when it is in use is thus provided with means for escape so that such gas does not tend to displace the electrolyte from about the anode in the brush. It will be apparent that either outlet path 115 for such gas could be employed alone to take care of the gas formed or both means of relieving such gas may be provided.

120 The brush illustrated in Fig. 3 is similarly made up of a brush head 7* having an apron 11* with bristles 9* set in the head, a handle 8*, and an anode 14* supported within the brush bristles by a shank 15*. This type of brush is particularly adapted for use where 125 the brush is frequently used on vertical sur-

faces or where it is applied to the underside, or horizontal surfaces. In such instances, with the shank 15^a extending through the brush head and the handle, the electrolyte 5 may tend to leak along the shank through the handle. To prevent this, a packing 24 is provided in the joint between the handle 8^a and the brush head 7^a. A series of vents 25 are arranged in the apron on the brush 10 head to allow for the escape of any gas formed during the electrolysis, and, to inhibit any leakage of electrolyte through these vents, they are arranged in a part of the apron 15 which is normally held in close contact with the brush bristles so that the brush bristles 20 act to retain the solution while permitting the escape of gas through the apertures.

The brush illustrated in Fig. 4 is of the same general construction as the brush illustrated in Fig. 1 except in the shape of the apron, in the absence of gas vents, and in the provision of packing about the shank supporting the anode. This type of brush 25 is particularly adapted for more or less continuous use in plating surfaces from the underside. Packing 24^b is provided in the joint between the brush head 7^b and the handle 8^b to prevent leakage of the electrolyte along the shank 15^b supporting the 30 anode. The apron 11^b, instead of closely contacting with the bristles 9^b just below the bristle setting and then gradually flaring outwardly, is cup shaped to provide a 35 free space about the bristles from the bristle setting toward the free end of the bristles. In use, the brush is dipped in the plating solution and inverted, the cup shaped apron 11^b serving to hold excess plating solution 40 and to prevent dripping from the brush bristles. In the inverted position, any gas 45 formed escapes toward the free end of the bristles. While a brush of this construction is of special utility for use in an inverted position, it is of more or less general application. Any gas formed when the brush is in an upright position tends to escape 50 through the free space within the apron rather than to displace electrolyte from about the anode.

50 In the round brush illustrated in Figs. 5 and 6, the anode 26 is in the form of a round rod arranged within the brush bristles 9^c and integral with the shank 15^c. Instead of being integral with the brush head 7^c, the 55 apron 11^c is separable therefrom. With some electrolytes, and where the brush is used but infrequently, the provision of a separable apron may be desirable to facilitate cleaning of the brush. The anode and 60 the supporting shank extend through the brush head and the brush handle 8^c to the adjustable supporting means on the upper end of the handle as in the brush illustrated in Fig. 1.

65 In using the improved brush of the present

invention, the anode in the brush is connected to the positive pole of a suitable source of direct current through the supporting shank, and the negative pole of the current source is connected to the conduct- 70 ing surface to be plated. The brush is then saturated with a suitable electrolyte, as by dipping in the electrolyte solution, and is applied to the surface to be plated. The plating solution is electrolyzed in the brush and the metal is deposited at the point of contact between the brush bristles and the conduct- 75 ing surface. The movement of the brush bristles over the conducting surface to be plated, the cathode, promotes effective de- 80 polarization at the cathode, so that the plating operation proceeds smoothly and uniformly. The distance between the end of the anode and the end of the brush bristles 85 is adjusted to promote uniform distribution of current flow through the electrolyte re- 90 tained by the brush without unduly increasing the resistance through the brush.

In using the brush of the present invention for nickel plating, for example, an electrolyte containing 281 gms. of crystallized nickel sulfate ($\text{NiSO}_4 \cdot 6\text{H}_2\text{O}$), 8 gms. of sodium fluoride, 30 gms. boric acid, and 2 gms. of glucose per litre may be used at ordinary temperature with a potential be- 95 tween the anode in the brush and the conducting surface to be plated of about 20 to 50 volts or somewhat less. The brush is advantageously connected in series with a 100 resistance large enough to render the varia- 105 tion in resistance in the brush when in use immaterial. For example, the brush may be connected to a 110 volt power line through a resistance of from about 25 to 40 ohms or more. For nickel plating, the 110 anode is advantageously made of nickel so that it will replace the nickel content of the electrolyte in the brush as the metal is plated therefrom. The shank supporting the anode 115 may also be of nickel, or of some material substantially insoluble in the electrolyte such as lead, or of some material lower in the electromotive series than nickel and which will not plate out of the solution such as 120 iron.

125 Advantageously, the anode is adjusted so that it does not come nearer to the surface to be plated than about the thickness of bristles around the anode. For example, in the brushes illustrated, the anode may be ar- 130 ranged about 1" from the end of the bristles when the brush is free from contact with the surface to be plated. It is also advantageous to arrange the anode so that it has a surface exposed to the electrolyte in the brush equal to or greater than the area of contact be- 135 tween the brush and the surface to be plated when the brush is in use. Current densities through the electrolyte in the brush of from 2 to 10 times those used in ordinary plating 140

bath practice may be employed and a consequent increase in the rate of deposition obtained without sacrifice of the quality or appearance of the metallic plating. Before 5 application of the plating with the brush, the surface to be plated may be cleaned and polished in any of the well-known ways.

We claim:

1. An improved brush for electroplating 10 conducting surfaces, which comprises a bristle head and an anode arranged with and surrounded by the bristles, an electrical connection to the anode, and a substantially rigid apron arranged about the bristles.
- 15 2. An improved brush for electroplating conducting surfaces, which comprises a bristle head and an anode arranged within the bristles, an electrical connection to the anode, and a substantially rigid apron arranged 20 about the bristles, the lower edge of the apron and the lower edge of the anode being arranged so that all straight lines through adjacent points thereof make an angle of less than 90° but not less than about 62° 25 with the axis of the brush.
- 30 3. An improved brush for electroplating conducting surfaces, which comprises a bristle head and an anode arranged within and surrounded by the bristles, an electrical connection to the anode, and a substantially rigid apron arranged about the bristles, and flaring outwardly therefrom toward the applied end of the bristles.
- 35 4. An improved brush for electroplating conducting surfaces, which comprises a bristle head and an anode arranged within and surrounded by the bristles, an electrical connection to the anode, a substantially rigid apron arranged about the bristles, and gas 40 relieving means communicating with the space within the apron.
- 45 5. An improved brush for electroplating conducting surfaces, which comprises a bristle head and an anode arranged within the bristles, an electrical connection to the anode, a substantially rigid apron arranged about the bristles in close contact with the bristles toward their fixed end and flaring away from the bristles toward their free end, and aper-

tures through the apron where it is in close 50 contact with the bristles.

6. An improved brush for electroplating conducting surfaces, which comprises a bristle head and a handle, an anode arranged within the bristles and supported on a shank 55 extending through the handle, means on the handle for adjusting the position of the anode along the axis of the brush, an electrical connection to the anode, and a substantially rigid apron arranged about the 60 bristles.

7. An improved brush for electroplating 65 conducting surfaces, which comprises a bristle head and a handle, an anode arranged within the bristles and supported on a shank extending through a hole in the bristle head and handle, means for relieving gas through the said hole, an electrical connection to the anode, and a substantially rigid apron arranged about the 70 bristles.

8. An improved brush for electroplating 75 conducting surfaces, which comprises a bristle head and a handle, an anode arranged within the bristles and supported on a shank extending through a hole in the bristle head and handle, the hole being large enough to provide a free space about the shank, an electrical connection to the anode, and a vent for relieving gas from the handle end 80 of the said hole.

9. An improved brush for electroplating 85 conducting surfaces, which comprises a bristle head and an anode arranged within the bristles, an electrical connection to the anode and means for relieving gas from the space in the bristles about the anode.

10. An improved brush for electroplating 90 conducting surfaces, which comprises a bristle head and an anode within the bristles, an impervious apron arranged about the bristles, an electrical connection to the anode, and means for relieving gas from the space in the brush within the apron.

In testimony whereof we affix our signatures.

EDWARD A. COADY.
FREDERIC W. OLMSTEAD.
